US00D849420S

(12) **United States Design Patent** (10) **Patent No.:** **US D849,420 S**
Yee et al. (45) **Date of Patent:** **** May 28, 2019**

(54) **FILM WITH PATTERN**

(71) Applicant: **The Glad Products Company**,
 Oakland, CA (US)

(72) Inventors: **Jacqueline E. Yee**, Cincinnati, OH
 (US); **Marian F. Smith**, Norwalk, CT
 (US); **Ranyi Zhu**, Bartlett, IL (US);
Shaun T. Broering, Fort Thomas, KY
 (US)

(73) Assignee: **The Glad Products Company**,
 Oakland, CA (US)

(**) Term: **15 Years**

(21) Appl. No.: **29/577,173**

(22) Filed: **Sep. 9, 2016**

(51) LOC (11) Cl. **05-06**

(52) U.S. Cl.

USPC **D5/60**

(58) **Field of Classification Search**

(57) **CLAIM**

The ornamental design for a film with pattern, as shown and described.

DESCRIPTION

The sole FIGURE is a top plan view of a film with pattern showing our new design.

The dot dash broken lines surrounding the FIGURE depict the boundaries of the claim and form no part thereof.

1 Claim, 1 Drawing Sheet
